UNITED STATES PATENT OFFICE.

MARTIN L. DETTINGER, JOHN A. WESPER, AND CARROLL SHEWELL, OF PHILADELPHIA, PENNSYLVANIA.

EXERCISING APPARATUS.

1,390,095.

Specification of Letters Patent. Patented Sept. 6, 1921.

Application filed September 28, 1920. Serial No. 413,267.

To all whom it may concern:

Be it known that we, MARTIN L. DETTINGER, JOHN A. WESPER, and CARROLL SHEWELL, citizens of the United States, residing in Philadelphia, Pennsylvania, have invented certain Improvements in Exercising Apparatus, of which the following is a specification.

The object of our invention is to provide an exercising apparatus of the "spring" type with means whereby an electric current can be passed through the body of the user of the apparatus while exercising.

In the accompanying drawings:

15 Figure 1 is a front elevation, illustrating our improved exercising apparatus;

Fig. 2 is a plan view;

Fig. 3 is a side view;

20 Fig. 4 is a sectional elevation of a portion of the base, showing the lower terminal posts;

Fig. 5 is a sectional elevation of the upper portion of the apparatus, showing the upper terminal posts;

25 Fig. 6 is a sectional view on the line 6—6, Fig. 1;

Fig. 7 is a detached sectional view, showing one of the lower binding posts and the parts connected therewith;

30 Fig. 8 is a detached sectional view of the upper binding post and the brush; and

Fig. 9 is a view illustrating a modification.

Referring to the drawings, 1 is a standard, rectangular in cross section in the present instance. This standard is secured to a base 2, which is arranged to be fastened to a floor in any suitable manner. The upper end of the standard is mounted in a socket 3 of a bracket 4 secured to a wall or other support, 40 as clearly shown in Fig. 3. In the two opposite corners of the standard are longitudinal slots 5, clearly shown in Figs. 3 and 6, for the reception of electric wires 7. Between the electric wires and the base and the sides 45 of the slots is a non-conducting strip 8. The exposed edge of the wire is preferably flattened, as shown in Fig. 6.

Adjustably mounted on the standard 1 is a cross head 9, which is split and has a transverse clamp screw 10 passing through one portion thereof and adapted to a thread in the upper portion so that the two portions can be drawn tightly against the standard, holding the cross head in the position in 55 which it is adjusted. Extending through the

cross head is a transverse, rectangular bar 11, which is held in position by screws 12. On this bar are adjustable clamp blocks 13, which are split, as shown in Fig. 3. 33 is insulation located between the blocks and 60 the bar. Clamp screws 14 extend through one portion of each clamp block and are screw threaded into the other portion so as to attach firmly the clamp blocks to the cross bar in the position to which they are adjusted. At the front of each clamp block is 65 an eye 15 and suspended from this eye is a spring 16 having a hand hold 17 at its upper end. This spring is the ordinary type of exercising spring now in common use in certain types of exercising apparatus.

In the base 2 are two binding posts 18 of ordinary type and a terminal screw 19 having a threaded end is adapted to a threaded opening in each binding post 18. This terminal screw has a head 20. The screw 19 extends through a bushing 21 of non-conducting material and the head fits against the shoulder in this opening. On the outer surface of the bushing is a screw thread 70 75 adapted to a threaded opening in the base 2.

The binding post terminal screw and bushing are clearly shown in the detached view, Fig. 7. The wire 7 extends into an opening in the terminal screw 19 and is 80 soldered therein.

Mounted on the cross head 9 are two terminal posts 22, which have threaded stems 23 adapted to a threaded opening in a non-conducting bushing 24. This bushing has 90 an external thread, which is adapted to a thread of an opening in the cross head, the parts being assembled as shown in Fig. 5. In the stem 23 is a recess 25 in which is located a contact brush 26. Back of this 95 brush is a spring 27, which tends to keep the brush in contact with the exposed portion of the wire 7. When the cross head is adjusted vertically and secured in the adjusted position, the two brushes 26 on opposite sides of the standard bear against the exposed wires in the slots in the standards.

On each clamp block 13 is a binding post 28 and a wire 29 extends from each binding post 22 on the cross head 9 to the binding post 28 on the clamp block so that, when a person exercising grasps the hand holds 17, a current of electricity passes through the arms and body of the person exercising.

The terminal posts 18 at the base are attached to any house service wire or to a battery. In some instances, instead of the binding posts 18 being located on the base, 5 they may be on a bracket 4^a at the upper end of the standard, as shown in Fig. 9. This bracket may have an extension 4^b, which may carry a transformer or medical 10 coil 30 connected to the binding posts 18^a on the bracket.

It will be seen that when an exercising apparatus of this type is used, an electric current will be passed through the body of the person exercising and the amount of 15 current can be regulated by any suitable resistance box placed in the circuit, but not shown in the drawings. The device can be adjusted to accommodate persons of different heights without breaking the electrical 20 connections.

Resting on the base 2 and surrounding the standard is a ring 31 of non-conducting material, preferably of rubber, which will prevent short-circuiting in the event of the 25 cross head falling. On the two bars 11 at each side of the cross head 9 are rings 32 and if the clamp blocks are moved against the rings 32 on the rod 11 they also prevent short circuiting.

30 We claim:

1. The combination in an exercising apparatus, of a standard; electric wires thereon; an adjustable cross head mounted on the standard and having bars projecting therefrom; clamp blocks adjustably mounted on the bars; a spring suspended from each clamp block; a handhold attached to each spring; contacts on the cross head adapted to bear upon the wires of the standard; and 35 connections between the adjustable clamp blocks and the contacts so that when the handholds are grasped an electric current will pass through the body of the person exercising.

40 2. The combination of a standard having a groove at each side; a wire located in each groove and having an exposed surface; an adjustable cross head mounted on the standard; brushes carried by the cross head and 45 adapted to bear against the exposed portion of the wires; and springs suspended from the cross head and having hand holds, each spring being connected to the brushes, so that, when the hand holds are grasped, an 50 electric current will pass through the body of the person exercising.

55 3. The combination in a standard, of a base in which the standard is located; a bracket supporting the upper end of the

standard, the standard being rectangular in 60 cross section and having longitudinal grooves at opposite corners; a wire located in each groove; a non-conducting strip back of each wire in its groove; binding posts on the base connected to the wires; an adjustable cross head having brushes arranged to bear against the exposed surface of the wires; a bar carried by the cross head; springs mounted on the bar and having hand holds, the brushes being electrically connected 65 with the hand holds and springs.

4. The combination of a standard; a base in which the standard is mounted; a bracket supporting the upper end of the standard, 70 said standard having two longitudinal 75 grooves therein; a wire mounted in each groove; means for placing the wires in an electric circuit; a cross head adjustably mounted on the standard, but held from turning thereon, said cross head having a 80 bar projecting at either side thereof; insulated clamp blocks mounted on the bar at each side of the cross head; exercising springs carried by each clamp block; hand holds suspended from the springs; brushes 85 mounted on the cross head and bearing against the wires of the standard and connected to the clamp blocks so that current passing through the wires will pass through 90 the body of the person exercising.

5. The combination of a base; a bracket; a standard supported by the base and bracket, said standard being rectangular in cross section and having longitudinal 95 grooves therein; a cross head adjustably mounted on the standard and having a rectangular bar projecting from each side thereof; clamp blocks mounted on the bars; exercising springs carried by the clamp blocks; hand holds suspended from the 100 springs; brushes mounted on the cross head; and connecting wires extending from the brushes to the clamp blocks.

6. The combination of a standard; a cross head mounted thereon; a bar projecting at each side of the cross head; adjustable clamp blocks mounted on the bar; exercising springs suspended from the clamp blocks; a ring of non-conducting material encircling the standard at its base to prevent the cross head coming in contact with the base; and a ring of non-conducting material encircling a bar at each side of the cross head so as to prevent the clamp blocks coming in contact 110 with the cross head.

MARTIN L. DETTINGER.

JOHN A. WESPER.
